[57] CLAIM

The ornamental design for an immunoassay test kit or the like, as shown and described.

DESCRIPTION

FIG. 1 is an exploded top, front perspective view of a immunoassay test kit or the like showing my new design, with the funnel portion removed;

FIG. 2 is a top plan view thereof, with the funnel portion attached;

FIG. 3 is a rear elevational view thereof;

FIG. 4 is a side elevational view thereof; and

FIG. 5 is a bottom plan view thereof.
